UNITED STATES PATENT OFFICE.

HORACE H. FISK, OF FLORENCE, OREGON.

BARREL-STAND.

SPECIFICATION forming part of Letters Patent No. 439,815, dated November 4, 1890.

Application filed July 25, 1890. Serial No. 359,905. (No model.)

To all whom it may concern:

Be it known that I, HORACE H. FISK, a citizen of the United States, residing at Florence, in the county of Lane and State of Oregon, 5 have invented certain new and useful Improvements in Barrel-Stands; and I do hereby declare the following to be a full, clear, and exact description of the invention, such as will enable others skilled in the art to which it appertains to make and use the same.

The special object of the invention is to make a stand by which barrels may be moved back and forth under a counter or shelf without the necessity of lifting so heavy a weight.

15 The drawing is a perspective view showing all the parts and their relative position.

In the drawing, A represents my barrel-stand as an entirety. It consists of the frame a, the shafts b b, which have the wheels c c, 20 journaled so as to turn on their ends, and the pivot d, which is screwed to the floor under the counter or shelf. The frame a consists of a metallic strip, which rests above the floor on one edge, while the other supports the 25 barrel. It is provided with an eye e, which turns on the pivot d, and with the offsets f f, into the ends of which pass the shafts b b, which are threaded to make them adjustable with respect to the frame a. The barrel is 30 set on the frame a so as to rest against the pivot d, when the shafts b b are screwed up into the frame until the shaft-pins g g abut

against the barrel. These pins d g g serve to always keep the barrel or half-barrel fixed in its place, and as the shafts are adjustable the 35 stand will hold securely a barrel of any size.

This stand is specially adapted for the use of stores or other places wherein barrels require to be frequently handled. The stand is angular and the pins d g g at equal distances apart, while the chines of the barrel 40 only touch the stand.

When it is desired to move a barrel from the under side of counter or shelf, the stand is swung around on the pivot d with very little 45 labor. I employ the key k or any other suitable device to prevent the spindles or shafts b b from turning or increasing their distance from the pivot d.

What I claim as new is—

50 In a barrel-stand, the combination, with a floor-pivot d, of the angular frame a, having the eye arranged to turn on the pivot d, the shafts b b, screwing into the offsets f f of said frame to make them adjustable with respect 55 thereto, and the wheels c c, arranged on the ends of said shafts, substantially as and for the purpose described.

In testimony whereof I affix my signature in presence of two witnesses.

H. H. FISK.
